Specification for Design.

Patented Aug. 2, 1921.

Application filed September 6, 1918. Serial No. 252,976. Term of patent 14 years.

To all whom it may concern:

Be it known that I, GEORGE W. BEADLE, a citizen of the United States of America, and a resident of New Rochelle, New York, (whose post-office address is 32 Siwanoy avenue, New Rochelle, New York,) have invented a new, original, and ornamental Design for a Correction-Indicator for a Dictation-Machine, of which the following is a specification, reference being had to the an-

nexed drawing, forming part thereof, and showing a perspective view of said indicator.

What is claimed is:—

The new and ornamental design for a correction indicator for a dictation machine as shown.

In testimony whereof, I have signed this specification.

GEORGE W. BEADLE.
